UNITED STATES PATENT OFFICE.

STERLING H. CAMPBELL, OF ST. LOUIS, MISSOURI.

DESIGN FOR A SPOON.

41,588.

Specification for Design. Patented July 18, 1911.

Application filed February 27, 1911. Serial No. 611,297. Term of patent 3½ years.

To all whom it may concern:

Be it known that I, STERLING H. CAMPBELL, a citizen of the United States, residing at the city of St. Louis, in the State of Missouri, have invented a new, original, and ornamental Design for a Spoon, of which the following is such a full, clear, and exact description as will enable any one skilled in the art to which it appertains to make the same, reference being had to the accompanying drawings, forming part of this specification.

Figure 1 of the drawings is a view showing the upper side or face of the spoon and Fig. 2 is a perspective view.

What I claim is:

The ornamental design for a spoon as shown.
